E. J. PAQUE,
REINFORCE BAR.
APPLICATION FILED SEPT. 30, 1921.

Patented Dec. 20, 1921.

Edward J. Paque

UNITED STATES PATENT OFFICE.

EDWARD J. PAQUE, OF CINCINNATI, OHIO, ASSIGNOR TO THE POLLAK STEEL COMPANY, OF CINCINNATI, OHIO, A CORPORATION OF OHIO.

REINFORCE-BAR.

1,400,570.

Specification of Letters Patent. Patented Dec. 20, 1921.

Application filed September 30, 1921. Serial No. 504,506.

To all whom it may concern:

Be it known that I, EDWARD J. PAQUE, a citizen of the United States of America, and a resident of Cincinnati, in the county 5 of Hamilton and State of Ohio, have invented a new and useful Improvement in a Reinforce-Bar, of which the following is a specification.

My invention relates to certain improvements in deformed reinforcing bars for concrete, as will be hereinafter more definitely pointed out.

An object of my invention is to produce a bar for the purpose stated wherein the lugs 15 formed on the bar may be extended therefrom at the greatest distance with the least possible weakening of the bar as a result thereof.

Another object is to provide a bar that is 20 easily rolled and upon which the lugs may be readily and easily formed.

These and other objects are attained by the means described herein and disclosed in the accompanying drawings, in which—

25 Figure 1 is a fragmental side elevation of a bar embodying my invention.

Fig. 2 is a sectional view on line 2—2 of Fig. 1.

Fig. 3 is a sectional view on line 3—3 of 30 Fig. 2.

The bar A may be round or oval in cross section and has formed on it the lugs a which extend radially from the body a' of the bar. The one end of each lug leaves 35 the body on a gradual curve at the end of which the lug attains its maximum width. From the place of the maximum width of the lug, the other end of the lug is precipitated sharply toward the body of the bar.

40 By providing the lug with this abrupt end a³, it is possible to give to the lug the maximum of bearing surface a² upon the concrete when embedded therein without seriously weakening the bar. This is readily

45 apparent by considering the quantity of material that would be taken from the body a' in order to continue any lug past the abrupt end and give to the lug beyond such abrupt end, a form similar to that portion 50 of the lug leading up to the abrupt end. The bearing surfaces a² of the lugs are inclined or tapered, whereby greater area is given thereto than were they formed parallel. This structure also facilitates the 55 forming of the lugs when the bar is passed

between the rolls employed to form said lugs.

The lugs extend through an arc of substantially 90° and are preferably spaced in pairs longitudinally of the bar, the lugs of 60 each pair being disposed substantially at diametrically opposed positions of the bar, and adjacent pairs of lugs being disposed in staggered relation. The immediately adjacent lugs of adjacent pairs of lugs have 65 their abrupt ends disposed in substantial alinement longitudinally of the bar. This gives a very firm set of the bar and concrete upon one another.

What I claim is:

70 1. A reinforcing bar for concrete comprising a body having a substantially spheroidal or spherical form in cross section, and lugs extending circumferentially of the body and each extending gradually outward from the 75 body at one end and terminating abruptly at its other end.

2. A reinforcing bar for concrete comprising a body having a substantially spheroidal or spherical form in cross section, and pairs 80 of lugs extending circumferentially of the body, each lug extending for approximately 90° of the circumference of the body and the diametrically opposed ends of the pairs of lugs extending gradually outward from 85 the body and terminating abruptly at their other ends.

3. A reinforcing bar for concrete comprising a body, and pairs of spaced lugs, each pair extending circumferentially of the body 90 and spaced from one another at approximately 90°, the lugs extending gradually outward from the body at one of their ends and terminating abruptly at the other of their ends, the abrupt end of one lug being 95 immediately adjacent of the gradually extending end of the other lug.

4. A reinforcing bar for concrete comprising a body, and pairs of spaced lugs, each pair extending circumferentially of the body 100 and spaced from one another at approximately 90°, the lugs extending gradually outward from the body at one of their ends and terminating abruptly at the other of their ends, the abrupt end of one lug being 105 immediately adjacent of the gradually extending end of the other lug, the lugs of adjacent pairs of lugs having their abrupt ends in substantial alinement longitudinally of the body.

5. A reinforcing bar for concrete comprising a body, and pairs of spaced lugs, the lugs of immediately adjacent pairs of lugs being disposed in staggered relation, each 5 pair extending circumferentially of the body and spaced from one another at approximately 90°, the lugs extending gradually outward from the body at one of their ends and terminating abruptly at the other of 10 their ends, the abrupt end of one lug being immediately adjacent of the gradually extending end of the other lug.
6. A reinforcing bar for concrete comprising a body, and pairs of spaced lugs, the lugs of immediately adjacent pairs of lugs being disposed in staggered relation, each 15 pair extending circumferentially of the body and spaced from one another at approximately 90°, the lugs extending gradually outward from the body at one of their ends and terminating abruptly at the other of 20 their ends, the abrupt end of one lug being immediately adjacent of the gradually extending end of the other lug, the lugs of adjacent pairs of lugs having their abrupt ends in substantial alinement longitudinally of 25 of the body.
7. A reinforcing bar for concrete comprising a body having a substantially spheroidal

or spherical form in cross section, and lugs 30 extending circumferentially of the body and each extending gradually outward from the body at one end and terminating abruptly at its other end, the sides of the lugs tapering gradually from the outermost portion 35 of the lugs to the body.

8. A reinforcing bar for concrete comprising a body, and pairs of spaced lugs, the lugs of immediately adjacent pairs of lugs being disposed in staggered relation, each 40 pair extending circumferentially of the body and spaced from one another at approximately 90°, the lugs extending gradually outward from the body at one of their ends and terminating abruptly at the other of 45 their ends, the abrupt end of one lug being immediately adjacent of the gradually extending end of the other lug, the lugs of adjacent pairs of lugs having their abrupt ends in substantial alinement longitudinally of 50 of the body, the sides of the lugs tapering gradually from the outermost portion of the lugs to the body.

In testimony whereof, I have hereunto subscribed my name this 29th day of September, 1921.

EDWARD J. PAQUE.
